Patented Dec. 17, 1957

181,737

RAIN HOOD

William B. Ligorner, New York, N. Y.

Application September 24, 1956, Serial No. 43,061

Term of patent 7 years

(Cl. D3—13)

Fig. 1.

Fig. 2.

Fig. 1 is a side perspective view of a rain hood showing my new design; the opposite side thereof being similar in appearance; and

Fig. 2 is an enlarged, fragmentary extended view thereof showing the surface ornamentation in detail.

I claim:

The ornamental design for a rain hood, substantially as shown and described.
